CLAIM

The ornamental design for an interbody bone implant, as shown and described.

DESCRIPTION

This application is related to U.S. patent application Ser. No. 29/404,922 entitled "Interbody Bone Implant," filed on Oct. 26, 2011, now U.S. Pat. No. D. 724,733 issued on Mar. 17, 2015, the disclosures of each U.S. patent application Ser. No. 29/404,921 and U.S. patent application Ser. No. 29/404,922 are incorporated herein by reference in their entireties. FIG. 1 is a front perspective view of an interbody bone implant according to an embodiment; FIG. 2 is a top view of the interbody bone implant illustrated in FIG. 1; FIG. 3 is a bottom view of the interbody bone implant illustrated in FIG. 1; FIG. 4 is a first side view of the interbody bone implant illustrated in FIG. 1; and FIG. 5 is a second side view of the interbody bone implant illustrated in FIG. 1; and, FIG. 6 is a cross-sectional view of the interbody bone implant taken along line 120-120 in FIG. 2. The broken-jagged lines which define the boundary of the claimed design do not form part of the claimed design. The broken lines are for environmental purposes only and form no part of the claimed design.
